UNITED STATES PATENT OFFICE.

BENJAMIN URIC, OF MILWAUKEE, WISCONSIN.

PUNCTURE-CLOSING DEVICE FOR TIRES.

Application filed August 31, 1921. Serial No. 497,405.

To all whom it may concern:

Be it known that I, BENJAMIN URIC, a citizen of the United States, residing in the city of Milwaukee, county of Milwaukee, and State of Wisconsin, have invented a certain new and useful Improvement in Puncture-Closing Devices for Tires; and I do declare the following to be a clear, exact, and complete description thereof, such 10 as will enable persons skilled in the art to which the invention relates to make and use the same, reference being had to the accompanying drawing for a disclosure of one form in which the invention has been embodied.

The object of my present invention is to simplify the construction shown in my prior Patent No. 1,313,868, granted to me on August 19, 1919, so as to enable a more economical production of like puncture closing devices to be achieved. The device disclosed in my prior patent involves in its manufacture some very expensive operations, which are completely eliminated in my 25 present invention. The operation of seating the needle in the handle of the patented construction has been most expensive and has induced me to simplify the device so as to avoid the necessity for the expensive operations heretofore performed.

The novel features of my present invention will be pointed out in the claims appended to this specification.

In the drawings which accompany this 35 specification,

Figure 1 is a view in side elevation of my improved puncture closing device, showing the manner of its use in connection with the repair of a punctured bicycle tire.

Fig. 2 is a plan view of the device shown in Fig. 1.

Fig. 3 is an enlarged fragmentary view in elevation opposite to that shown in Fig. 1.

Fig. 4 is a sectional view on the line 4—4, 45 Fig. 3, looking in the direction of the arrow.

It has long been the practice to repair punctured tires by the use of devices adapted to serve a rubber band in attenuated condition with several parallel windings, so that when the band is inserted in the puncture, and a closing cement applied thereto, the band will expand when released by the serving device, with the effect of completely 55 and effectively closing the puncture.

In my prior patent I utilize the tension

of the elastic band to hold the supporting hook in operative position so that by merely turning the hook at the proper time, the tension of the band would be relaxed. 60

In the present invention I make use of the same principle of operation disclosed in my former patent, but have greatly simplified the construction of the device whereby the results desired are attained. 65

Referring now to the drawing, the numeral 10 indicates a handle which may be economically produced by stamping or casting. The forward end of the said handle is formed with a projection 11 so as to stand at 70 an angle to the direction of the length thereof, and is provided with a perforation 12, through which the needle 13, having a fork 14 at its free end may be passed. The rear end of the needle is formed with an eye 14' 75 adapted to be brought into registry with a perforation 15 extending transversely of the handle and properly located with reference to the length thereof. In forming the perforation 15, a boss 16' is extruded upon the 80 side of the handle opposite to that upon which the projection 11 is formed. The end of the needle is passed through the opening 12, in the projection 11, and the eye 14' is brought into registry with the perforation 85 15 in the handle. A tubular rivet 16 is passed through the eye of the needle and the perforation 15, and the pointed end thereof is spread upon the boss 16' to unite the needle firmly to the handle, with the parts in 90 close engagement as indicated in Fig. 2.

The tubular rivet forms a journal bearing for the shank 17 of the hook 18, which normally supports the band extending from the forked end of the needle. As before stated, 95 the tension of the band retains the hook in proper position for insertion in the puncture in the tire and it is necessary in discharging the band into the puncture only to press the lever 19 of the hook with the thumb or 100 finger, to rotate the shank 17 in its journal and free the distended band from its engagement with the hook, as in my prior patent.

The construction embodied in my present invention is extremely simple and most economical in production, it having all of the efficiency of my former patented device and several advantages from an economical standpoint. 105

It will be observed that the points of attachment of the needle to the handle are separated by a considerable distance, and 110

that that part of the needle extending between the points of attachment, lies in close parallelism with the handle. By means of this construction the needle is firmly held in position upon the handle, the arrangement being one which produces a rigid construction, and insures the satisfactory operation of the device in performing its intended functions.

10 Having thus described my invention, what I claim, and desire to secure by Letters Patent of the United States, is:

11 1. In a puncture closing device for tires, the combination of a handle and a needle, the latter being forked at its free end and provided with an eye by means of which it is attached to the handle, with a hook journaled in the handle and adapted to be held in operative position by an elastic band extending from the fork of the needle, and to be turned to disengage the elastic band from the hook.

12 2. In a puncture closing device for tires, the combination of a needle forked at its free end and provided with an eye at the other, a handle having a projection at one end provided with means for engaging the needle at an intermediate point, and means passing through the eye of the needle to secure the latter to the handle, with a hook pivoted on the handle and adapted to be held in operative position by a distended elastic band, and to be turned to disengage the elastic band from the hook.

13 3. In a puncture closing device for tires, the combination of a handle, a needle provided with a fork at its free end and secured to the side of the handle at its other, the said handle being provided with means

for engaging the needle at an intermediate point, with a band retaining hook pivoted to the handle and adapted to be held in operative position by an elastic band when taut, and to be turned to disengage the elastic band from the hook.

14 4. In a puncture closing device for tires, the combination of a needle forked at its free end and provided with an eye at the other, and a handle provided with means for engaging the needle at a point intermediate its length, and an eyelet passed through the eye of the needle to secure the same to the handle at a point intermediate the ends of the latter, with a hook pivoted in the eyelet and held in operative position by an elastic band when taut and adapted to be turned to disengage the elastic band from the hook.

15 5. In a puncture closing device for tires, the combination of a needle provided with a fork at its free end and an eye at the other, a handle provided with a projection for engaging the needle at a point intermediate the ends of the latter and a perforation adapted to register with the eye of the needle, a tubular rivet passed through the eye of the needle and the perforation in the handle to unite the parts, with a hook journaled in the tubular rivet and adapted to be held in operative position by an elastic band when taut, and to be turned to disengage the elastic band from the hook.

16 In testimony whereof I have signed my name at Milwaukee this 24th day of August 1921.

BENJAMIN URICH.
